(57) **CLAIM**

The ornamental design for a combined wiring device with multiple power delivery ports, as shown and described.

DESCRIPTION

FIG. 1 is a front perspective view illustrating the combined wiring device with multiple power delivery ports design according to another embodiment;

FIG. 2 is a rear perspective view thereof;

FIG. 3 is a front plan view thereof;

FIG. 4 is a rear plan view thereof;

FIG. 5 is a right side view thereof;

FIG. 6 is a left side view thereof;

FIG. 7 is a bottom plan view thereof;

FIG. 8 is a top plan view thereof;

FIG. 9 is a front perspective view illustrating the combined wiring device with multiple power delivery ports design according to another embodiment; and,

FIG. 10 is a rear perspective view thereof.

The broken lines depict portions of the combined wiring device with multiple power delivery ports and form no part of the claimed design.

1 Claim, 9 Drawing Sheets
